UNITED STATES PATENT OFFICE

ULISES A. SANABRIA, OF LOUISVILLE, KENTUCKY, ASSIGNOR, BY MESNE ASSIGNMENTS,
TO WESTERN TELEVISION CORPORATION, OF CHICAGO, ILLINOIS, A CORPORATION OF
DELAWARE

METHOD AND MEANS FOR SCANNING

Application filed June 7, 1929. Serial No. 369,169.

My invention relates to apparatus for broadcasting and receiving visual images and pictures and more particularly to a novel scanning device and method for analyzing 5 the image or object which is desired to be transmitted and received either by wireless or wired television.

Heretofore methods employed for scanning or covering a picture surface have used 10 a rotating or other movable member provided with suitable analyzing elements for controlling pencils of light adapted to sweep over the image or picture surface from one of its sides to the other and in succession 15 from top to bottom or vice versa, once for each revolution or complete cycle.

Obviously, such scanning methods cause 20 the picture surface to be traversed by a series of light pencils which sweep over the picture surface in successive adjacent paths with the result that successive scan lines or 25 paths have practically the same shading characteristics in other than certain geometrical images, and since electrical impulses given off or controlled by the photo-electric 30 cells, so placed as to receive the light changes from the image being transmitted, derive their wave form characteristics from the shading of the image, it is obvious that successive 35 electrical impulses will possess similar wave shape and frequency characteristics corresponding to the shading characteristics of said image.

It is well known that all electrical circuits 40 exhibiting selective frequency characteristics possess a certain amount of electrical inertia, that is any certain wave form must be repeated a certain number of times in order for this inertia to be overcome and the transient to disappear, thus permitting the signal to reach an optimum.

When the above system of scanning is utilized, similar wave forms are repeated several 45 times, thereby giving effectual duration sufficient to overcome said inertia and permit the signals to build up sufficiently to affect the selective qualities of an electrical circuit having selective frequency characteristics. 50 This building up of signal frequency causes

undesirable interference due to the widening of the so-called side-bands.

I propose to eliminate this objectionable interference caused by the side-bands by interposing dissimilar wave forms so that no 55 particular wave form will be repeated a sufficient number of times to overcome the inertia of the circuit having selective frequency characteristics, therefore, a signal is not permitted to build up to sufficient strength 60 to be a factor within the range of practical perceptibility.

One method of accomplishing this interposition of frequencies is to provide a scanning disc having analyzing elements arranged so that successive elements of rotation 65 do not scan adjacent segments of the image. In other words, the probability is that the successive lines of scanning will possess vastly different shading characteristics. 70

It follows that the electrical wave shapes generated by the photo-electric cells, when such a scanner is used, will possess different wave form characteristics and therefore, no one wave shape will be repeated a sufficient 75 number of times to enable the inertia of the electrical circuits involved to be overcome and no one wave shape will have sufficient duration to give rise to audible side-band interference, thereby eliminating all interference within the limits of practical perceptibility. 80

It is an object of my invention to obtain the foregoing by using a scanning member having its analyzing elements so arranged 85 that for each complete cycle a plurality of coarse scans of the image are made. These coarse scans being offset from one another in such a manner that their combined effect for each complete cycle is a fine scan. 90

A further object of my invention is to provide a method of image transmission which will scan or cover the image or picture surface to be transmitted with a plurality of light pencils adapted to traverse the picture surface in a plurality of adjacent paths but with successive light pencils traversing the picture surface in non-adjacent paths. 95

A further object of my invention is to provide a novel, comparatively simple and ef- 100

fective method and apparatus whereby the definition of the image is materially increased without necessitating a corresponding increase in the light impulse frequency, or, conversely, whereby the light impulse frequency and resulting electrical frequency are decreased without a corresponding decrease in definition.

Another object is to provide a method for rapidly covering the area of the object or picture to be transmitted within the time of persistence of vision, that is, twelve to sixteen times per second without involving too high a speed and which will reduce the flicker at both the transmitting and receiving stations.

A further object of this invention is to provide a rotating scanning disc having a series of apertures or analyzing openings each situated at a different distance from the center of rotation and arranged in more than one spiral.

My invention will be better understood from the following description taken in connection with the accompanying drawings and its scope will be pointed out in the appended claims.

Referring to the drawings, Figure 1 is a plan view of my improved scanning disc; Figure 2 is a diagrammatic sketch illustrating the manner in which the image or picture field is scanned or analyzed and composed or built up; Figure 3 shows another disc embodying my invention; Figures 4 and 5 are sketches showing the radial arrangement of the apertures; Figure 6 shows a perforated ribbon or band; and Figure 7 is a schematic drawing showing one way of carrying out my method.

The scanning disc shown in Figure 1 comprises a disc 10 of some suitable material such as aluminum having holes 11 near its center for mounting to any suitable driving means such as an electric motor (not shown) for rotation about center O. Scanning or analyzing apertures 12 are formed, by drilling or otherwise, near the periphery of the disc 10. For convenience, I have illustrated a disc having only fifteen apertures, although I prefer to use a greater number, as for instance forty-five, but since the principle is the same regardless of the number of apertures used, a disc having fifteen apertures will suffice for the purpose of giving a complete description and disclosure of my invention. The apertures 12 are equally spaced angularly which, in the present case of fifteen apertures, is twenty-four degrees (24°) and are arranged in the form of three spirals. Each aperture 12 is located a different distance from the center O of the disc 10.

A description of a method of layout for a fifteen hole disc will best describe the exact arrangement of the apertures 12 on the disc.

10. First of all fifteen equally spaced radii

r are inscribed on the disc 10. Then fifteen equi-spaced concentric circles c are drawn having as their center the center of rotation O of the disc 10. The distances between the concentric circles c should equal or be less than the diameter of the apertures 12 which are to be formed.

The intersections of the radii r and the concentric circles c determine the centers of the apertures 12 which are located in the following manner: Starting with spiral I an aperture 12 is formed at the intersection of the radial line r and the outmost circle c. Going clockwise twenty-four degree (24°) another aperture is formed at the intersection of a radial line r and the fourth circle c counting towards the center O. This process is repeated for the remaining three apertures 12 of spiral I so that each aperture of rotation is radially spaced from the proceeding aperture by the distance between three of the concentric circles c which is the distance between adjacent circles times the number of spirals. The apertures in spiral II are located or situated in the same way except that the first aperture 12 of the spiral II is located on the intersection of its radial line r and the second concentric circle c counting towards the center O. The same applies to spiral III which has its first aperture located on the third circle c counting from the outmost circle towards the center O.

From this it is observed that the first aperture 12 in spiral II is radially spaced from the first aperture 12 in spiral I by the distance between adjacent circles c.

For a more complete understanding of the exact arrangement of the apertures 12 in the various spirals reference is made to Figures 4 and 5 in which the radial lines r have been rotated about the center O to bring the apertures 12 into close proximity with one another. From the arrangement of the apertures 12 it can be seen that the apertures 12 in spiral I will coarsely scan the entire image or picture field and that spirals II and III will also coarsely scan the entire image or picture field in succession. Due to the fact that no two of the apertures 12 scan the same elements of the image or picture field, it is evident that the combined effect of the three coarse scans is to give a fine scan or detailed analysis of the entire image or picture field for each revolution of the scanning disc 10.

This combining of coarse scans to build up a fine scan is illustrated in Figure 2 in which A indicates the elements of the image or picture which are analyzed by spiral I and B and C indicate the elements analyzed by spirals II and III respectively. For each revolution of the scanning disc 10 the coarse scans of spirals I, II and III are interposed to form the fine or complete scan represented by D.

It is obvious that my invention may take

various forms such as shown in Figure 3 where a six spiral disc is represented in which some of the spirals alternate, that is, scan from bottom to top while the other spirals scan from top to bottom. As in the case of the three spiral disc the coarse scans of each spiral fit together to form a fine or complete scan.

Without changing my method the apertures may be formed in a ribbon or band as shown in Figure 6 in which the apertures are arranged in a series of groups so that each group will coarsely scan the image and the resultant of all the groups will form a fine scan in the same manner as a disc made in accordance with my invention as above described.

In Figure 7 the disc 10 having apertures 12 made in accordance with my invention is intended to be rotated between a source of light L and a picture surface S shown edge on.

When the aperture 12 is in front of the light L the pencil of light strikes the picture surface S near the top, as shown in full line; when some other aperture 12 is in position the pencil of light strikes the picture surface S near the bottom, as indicated by the broken line; when other apertures come into position the light pencils strike in different positions between these extremes.

It will readily be understood that upon rotating my improved disc that light pencils will travel across the picture surface from side to side; while the arrangement of the apertures in more than one spiral causes successive light pencils to traverse the picture surface in non-adjacent paths, the adjacent paths being traversed by non-successive light pencils.

In reception the light source L is an illuminant modulated in accordance with the received signals and the image is built up on the surface S in the same sequence in which it was analyzed for transmission, that is, a series of coarse scans interposed to form a fine scan. This building up of the entire image simultaneously does away with the crawling effect observed when a single spiral disc is used and reduces flicker in the received image.

While I have shown the analyzing elements to be small round holes or apertures my invention is not limited thereto, but obviously includes the use of apertures having any other shape such as square or oval and also includes the use of lenses, prisms and mirrors which are well known in the art since all are equally adapted to my improved method of scanning.

I have found in using a scanning device made in accordance with this invention for the transmission and reception of images or pictures that for the same speed of scanning and the same number of apertures the fidelity and definition of reception is far better than

when using the ordinary disc having a single spiral.

I have also found with the use of my improved scanning method that it is possible to transmit and receive half-tone images having satisfactory definition and fidelity without exceeding the broadcast band perceptibly.

I believe that the interposition of frequencies as above explained, obtainable by my novel method of scanning, is the controlling factor which enables me to transmit and receive half-tone images without using a band of frequencies greater than required for first-class voice and music broadcasting.

While I have described a particular embodiment of my invention, and certain apparatus for carrying out my method, it will be obvious to those skilled in the art that various modifications may be made without departing from the spirit of my invention and I, therefore, desire to cover all such modifications as fall within the scope of my invention which is set forth in the appended claims.

What I claim as new and desire to secure by Letters Patent of the United States is:

1. In apparatus of the class described an optical analyzing unit comprising a rotating disc provided with a plurality of apertures arranged in more than one spiral and so positioned that each aperture describes a separate circular path about the center of rotation.

2. In apparatus of the class described an optical analyzing unit comprising a rotating disc provided with a series of apertures arranged in a plurality of spirals to sweep over an image and so arranged that the apertures in each spiral make a complete coarse scan of the image offset from that of the other spirals.

3. A rotating scanning disc provided with a plurality of apertures each situated at a different distance from the center of rotation and so arranged that the distance from the center of rotation of successive apertures of rotation differ more than that of some non-successive apertures of rotation.

4. A rotating scanning disc provided with a series of analyzing elements each situated at a different distance from the center of rotation and arranged in more than one spiral.

5. Scanning apparatus for the transmission of images electrically, comprising a disc having a plurality of analyzing elements so arranged that upon rotation of the disc the successive analyzing elements of rotation follow non-adjacent paths.

6. In an apparatus of the class described an optical analyzing unit comprising a moving member provided with a plurality of analyzing elements arranged to sweep over an image in non-adjacent parallel paths.

7. In combination, a stationary picture surface, a stationary light translating element, a rotatable disc interposed between said surface and said element, said disc being pro-

vided with a plurality of apertures so arranged that upon rotation of the disc the apertures pass successively between said surface and said element and successive images of the light translating element traverse the picture surface by non-adjacent parallel paths.

8. A scanning disc provided with a plurality of apertures arranged on a plurality of spirals in such a manner that any aperture on one spiral appears on a radius equal to the radius of the corresponding aperture on any other spiral, plus or minus an integral number of aperture diameters.

15. A scanning disc provided with a plurality of apertures arranged on a plurality of spirals in such a manner that successive apertures of rotation are radially displaced from each other by a distance greater than the diameter of an aperture.

20. A rotating scanning disc provided with a plurality of analyzing elements each analyzing element being located on a single circle of a series of concentric circles, said concentric circles being equi-spaced apart from each other and said analyzing elements being so arranged that successive analyzing elements of rotation lie upon non-adjacent circles.

11. A rotating scanning disc provided with a plurality of apertures situated on equi-spaced concentric circles having a common center coinciding with the center of rotation of the disc and so arranged that successive apertures of rotation lie on non-adjacent circles.

25. A scanning disc having a center of rotation and provided with a plurality of apertures spaced angularly near the periphery thereof and arranged in such a manner that successive apertures of rotation are radially displaced from each other by a distance greater than the diameter of any one aperture.

13. In a television receiver an illuminant adapted to be modulated in accordance with incoming signals, scanning means for composing an image from said signals comprising a disc having a plurality of analyzing elements so arranged that upon rotation of the disc the successive analyzing elements of rotation follow non-adjacent paths.

In testimony whereof I have affixed my signature.

ULISES A. SANABRIA.
